(57) CLAIM

The ornamental design for a tracking device mount, as shown and described.

DESCRIPTION

FIG. 1 is a top perspective view of a tracking device mount showing the new design;

FIG. 2 is a front elevation view thereof, the rear elevation view is a mirror image;

FIG. 3 is a top view thereof;

FIG. 4 is a bottom view thereof; and,

FIG. 5 is a side view thereof.

The dashed lines shown in the drawings illustrate portions of the tracking device mount that form no part of the claimed design.
